UNITED STATES PATENT OFFICE.

WALTER L. SIEWERS, OF WINSTON-SALEM, NORTH CAROLINA.

DESIGN FOR AN UNDERGARMENT.

43,785.

Specification for Design.

Patented Apr. 1, 1913.

Application filed December 7, 1912. Serial No. 735,535. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of tubular knit fabric 1 having the wales of the knitting running longitudinally of the fabric and garment, such tubular fabric being cut from opposite sides as at 2 upon the curves shown and also cut in a V-shaped cut at the front as at 3

and a V-shaped cut 4 at the back, both of such V-shaped cuts being lower in their lower limits than the cuts 2, the front V-shaped cut 3 being lower than the back cut 4. The waled fabric is continued in narrow strips integral with the body 1 as at 5 to form shoulder straps and the cut edges are bound throughout by an ornamental binding or beading 6 which extends entirely around the cuts 2, 3 and 4 and over the shoulder straps at the sides of the fabric strips 5.

I claim—

The ornamental design for an undergarment as shown and described.

WALTER L. SIEWERS.
